UNITED STATES PATENT OFFICE.

CHARLES F. ROOT, OF RAVENNA, OHIO, ASSIGNOR OF ONE-FOURTH TO BYRON O. CONN,
OF MANSFIELD, OHIO.

SAFETY DEVICE.

1,169,512.

Specification of Letters Patent. Patented Jan. 25, 1916.

Application filed February 6, 1915. Serial No. 6,420.

To all whom it may concern:

Be it known that I, CHARLES F. Root, a citizen of the United States of America, residing at Ravenna, in the county of Portage and State of Ohio, have invented certain new and useful Improvements in Safety Devices, of which the following is a specification.

This invention relates to safety devices 10 for printing presses, though equally applicable to machines equipped with a movable element that is adapted to exert a pressure upon work or the like which is interposed between said element and an opposing element.

It is well known that the operator of a machine who is required to place work between and remove work from between a movable pressure element and an opposing 20 element by hand manipulation is in great danger of being injured by inadvertently or otherwise failing to remove the hands or fingers from between the elements in time to prevent the hands or fingers of the operator from being caught, pressed and crushed between said elements.

The primary object of this invention therefore is to provide means of insuring absolute safety to the operator of a machine 30 of the class described although by inadvertency or otherwise the operator's fingers or hands should be caught between the elements.

My invention more specifically consists in 35 employing a movable work engaging element that is normally operative to exert a pressure at a pre-determined point in its working movement, said pressure being preferably exerted upon the movable work 40 engaging element just prior to contacting with and while it is acting upon the work that is interposed or projected between the movable work engaging element and a resisting opposing element; and automatic 45 means to render the movable work engaging element inoperative to exert a pressure when in its working movement it encounters an obstruction extraneous to the work which subjects it to a pressure before it reaches the 50 pre-determined point at which it is operative to exert a pressure.

Another object of this invention is to provide machines of the class described with an automatic safety device that will prevent 55 injury to the operator irrespective of

the fact as to whether or not his mind is upon the work.

The above objects are set out in my application bearing date of November 24, 1914, Serial No. 873,778 and the present invention has the same objects in view and consists in the construction of new elements, arrangements thereof, and means of combining them to accomplish the objects or results above described.

A further object is to reduce to a minimum the weight of the work engaging element and to provide facilities for resisting pressure thereon transmitting it to the face of the work engaging element and distributing it upon the whole area of the face in substantially equal proportions.

This invention comprises a duplex work engaging element, the parts of which are linked together and a slidable locking means 75 to automatically connect the parts to exert a pressure upon an opposing element, said means being also automatically operable to permit one of the parts to yield with relation to the other upon being subjected 80 to pressure before the parts are connected for exerting a pressure upon the opposing element.

A further object is to prevent the duplex work engaging element from exerting a 85 pressure upon work interposed between it and the opposing element by means which is manipulated by hand, said means also being adapted to continuously or periodically prevent said work engaging element 90 from exerting a pressure upon the opposing element at the will of the operator.

I attain these and other objects by the mechanism illustrated in the accompanying drawing, in which:

Figure 1 is a side elevation partly in section of a conventional type of a job printing press showing the safety device applied thereto. The duplex work engaging element is shown in a position to yield, in full 100 lines, and rigidly connected together for exerting a pressure, in dotted lines. Fig. 2 is a side elevation of the press showing the relative positions of the parts of the duplex work engaging element and operating mechanism when the duplex element has been subjected to pressure, to wit: by the fingers or hands of the operator, prior to its acting upon the work. Fig. 3 is a plan view of the duplex work engaging element and mecha- 105 110

nism shown separated from the press in locked position. Fig. 4 is a sectional detail view on the line X-X of Fig. 3 showing the application of a friction spring. Fig. 5 is a rear elevation of the press and safety operating mechanism. Fig. 6 is a detail view of the method of connecting the rebound coil springs.

Referring to the drawings, reference numeral 1 depicts a frame, 2 the platen, 3 and 4 the crank disks and 5 and 6 the connecting rods of an ordinary job printing press. One part 7 of a duplex work engaging element is provided with legs 8 and 9 and pivotally mounted upon a shaft 10. The part 7 is provided with a series of corrugations 11 (preferably of a rectangular shape). The other (or auxiliary part) 12 of the duplex work engaging element is also pivotally mounted upon the shaft 10.

The parts 7 and 12 comprising the duplex work engaging elements are yieldingly linked together for movement in unison and independent of each other by the links 13 and 14 which are provided with solts 15. A locking member 16 is provided with a series of corrugations 17 and is slidably secured to the part 12 by the bolts 18 which are inserted in the slots 19 and threadably connected to the part 12 and maintain the leaf spring 20 in frictional sliding contact with the part 12.

The locking member 16 is provided with standards 21 and 22 and a shaft 23 is journaled in the ends forming a yoke like structure. The part 12 is provided with wings 24 and 25 and suitable bearings are formed therein to journal a rock-shaft 26. Arms 27 and 28 having their ends bifurcated to movably engage the shaft 23 are rigidly secured to the rock shaft 26 by any well known fastening means. A lever 29 having a cam 30 formed on its free ends is rigidly secured to the rock shaft and is located and adapted to travel in the path of the nose 31 of the contact lever 32 which is pivotally mounted upon a standard 33 which is in turn secured to and supported by the bars 34 and 35.

The contact lever is preferably made in the form of a bell crank and pivotally mounted upon the standard 33. The part 36 of the bell crank contact lever is weighted to normally hold the contact lever 32 in contact with the stop pin 37. The retractile springs 38 and 39 which are attached to the arms 27 and 28 and to the part 12 normally exert pressure to force the locking member 16 to the position shown in Fig. 1, dotted lines, or in other words forcing the ends of the ridges of the corrugations 11 and 17 in a position to abut against each other.

The springs 40 and 41 are attached to the arms 27 and 28 and to a brace 42 to provide a cushion for the rebound of the locking member. The hooked end 40¹ and 40² of the springs 40 and 41 are attached to

a lug 43 through the medium of the slot 44 which allows for play of the hooked ends of the spring and prevents the tension of the springs from being exerted upon the locking member for cushioning purposes until the locking member has been forced to or is adjacent to its normal position thereby interlocking the parts of the duplex work engaging element.

The operation of the safety device in its application to a conventional type of jobbing press as shown in the drawings, is as follows: When movement is imparted to the disks 3 and 4 it is transmitted to the links 5 and 6 thence to a shaft 45 which is journaled in suitable bearings formed in the part 12 causing the part 12 and part 7 which is linked to it to oscillate or reciprocate. The parts 7 and 12 comprising the duplex work engaging element are normally interlocked by the locking member 16, the springs 28 and 29 forcing the locking member to move to and yieldably remain in a position in which the ends of the ridges of the corrugations of the parts 7 will be directly in line with and abutting against the ends of the ridges of the corrugations of the locking member 16 (see dotted lines, Fig. 1).

When the duplex work engaging element has traveled to a pre-determined point in its working stroke, the cam 30 on the lever 29, comes in contact with the nose 31 of the contact lever, the tension of the springs 38 and 39 are counteracted and the locking member is forced to slide to the position shown in Fig. 1, full lines, leaving the ridges of the corrugations of the locking member and the ridges of the corrugations of the part 7 in positions opposite the channels of the corrugations preparatory to being telescoped therewith.

If the duplex work engaging element is subjected to pressure when in the above described position, or an obstruction (such as the hands or fingers "a") is interposed between the work engaging element and the opposing element, during the time that the cam is in contact with the nose 31, the corrugated part 7 will yield, the corrugations of the part 7 and corrugations of the locking member 16 telescoping with each other and when the pressure is relieved or the obstruction removed, the part 7 will by gravity move to the position shown in Fig. 1, full lines, thereby permitting the springs 38 and 39 to force the locking member to slidably move to a position that the ridges thereof will be in alignment with and in position to abut against ridges of the part 7 as shown in dotted lines, Fig. 1, thereby rigidly interlocking the parts of the duplex work engaging element for exerting a pressure.

The cam 30 is arranged and made of such proportions and dimensions that it is forced to contact with the nose 31 at a pre-determined point in the working movement of

the duplex work engaging element and will preferably remain in contact therewith until the duplex work engaging element is about to act upon the work, the cam is then released from engagement with the nose 31 and the springs 38 and 39 force the locking member to interlock the parts of the duplex work engaging element for pressure upon the work that is interposed between it and 10 an opposing element.

It will be noted that the parts comprising the duplex work engaging element can be interlocked or unlocked at pre-determined points in its working movement by simply 15 varying the dimensions of the cam or arranging the cam to contact with and be released from the nose 31 at a pre-determined point in the working movement of the duplex work engaging element.

20 To provide hand manipulated means for periodically or continuously preventing the duplex work engaging element from exerting a pressure upon the work interposed between both elements, a lever 46 is pivotally attached to the frame and is connected to a bell crank 47 by a link 48. When it is desired to continuously or periodically prevent the work engaging element from exerting a pressure, the lever 46 is operated to throw 25 the crank lever to the position shown in dotted lines, the end 49 will then contact with leg 8 and exert a pressure thereon thereby preventing the parts from being interlocked. The hand manipulated mechanism can be 30 used to perform the functions of what is called a "throw off" in the printing press art.

What is claimed is:

1. The combination with a duplex work performing element and its actuating means, of 40 normally collapsible connections between the parts of the duplex element including a sliding member operable to permit said parts to collapse, and means whereby said member is operated during the operative movement of the duplex work performing element and just prior to the engagement of said element with the work and when the path of the element is free to render said connections rigid against collapsing.

50 2. The combination with a duplex work performing element and its actuating means, of normally collapsible connections between the parts of the duplex element comprising a sliding corrugated member operable to permit said parts to collapse, and means whereby said member is operated during the operative movement of the duplex work performing element and just prior to the engagement of said element with the work and when the path of the element is free to render said connection rigid against collapsing.

60 3. The combination with a duplex moving element of a machine and its actuating means, of normally yieldable connections between the parts of the duplex element adapt-

ed to yield when movement of said element is resisted, one of the parts of said duplex element being provided with corrugations, said connection comprising a sliding corrugated member and means to automatically 70 render said connection operable to prevent the parts of said duplex member from yielding and to permit said parts to yield when it encounters resistance in its operative movement prior to contacting with the work. 75

4. The combination with a duplex moving element of a machine and its actuating means, the duplex element comprising normally yieldable and relatively movable parts, a sliding member to rigidly connect said parts at a predetermined point in the operative movement of said duplex element, and means whereby the parts of said duplex element may move relatively to each other when movement of said duplex element is resisted by an extraneous obstruction before said predetermined point is reached. 80

5. In combination with a duplex reciprocating member, means to actuate said duplex member, a sliding member interposed between the parts of the duplex member, and automatic means to actuate said sliding member to force it to a position to permit the parts of the duplex member to collapse 90 if it meets with resistance before it reaches a predetermined point in its operative movement. 95

6. In combination with a duplex reciprocating member, one of the parts being provided with corrugations, a sliding corrugated member interposed between the parts of the duplex member and in one position having its corrugations engageable with the corrugations of said part, automatic means to operate the sliding member to rigidly connect the parts of the duplex member by said engagement of the corrugations for exerting a pressure, and automatic means to operate the sliding member to force it in a position to permit the duplex member to yield when it encounters an obstruction before it reaches a predetermined point in its working movement. 100

7. In combination with a duplex movable work engaging element, a sliding member interposed between the parts of the duplex member, automatic means to force the sliding member in a position to interlock the parts of the duplex member at a pre-determined point in its working movement, and automatic means to prevent the sliding member from interlocking the parts of the duplex member if subjected to resistance before it reaches said pre-determined point. 110

8. In combination with a duplex movable work engaging element, a sliding member interposed between the parts of the duplex member, automatic means to force the sliding member to a position to interlock the parts of the duplex member at a pre- 120

- determined point in its working movement, 5
automatic means to prevent the sliding member from interlocking the parts of the duplex member if subjected to resistance before it reaches said pre-determined point, and 10
manually operated means to periodically or continuously prevent the parts of the duplex element from interlocking on its working stroke.
- 10 9. In combination with a duplex reciprocating element to act on the work, and actuating means for said element, a sliding member interposed between the parts of the duplex element, means to operate the sliding member to rigidly connect the parts of the duplex element for exerting a pressure at a pre-determined point in its working movement, and means to operate the sliding member to permit the duplex element to yield if subjected to pressure before it reaches 20
said pre-determined pressure point.
- 10 10. In combination with a duplex reciprocating member to act on the work, and means to actuate said member, the parts of the duplex member being connected and adapted to be moved in unison and independent of each other, a sliding member interposed between the parts of the duplex member, and means to automatically operate said sliding member to rigidly interlock the parts for pressure and movement in unison and to permit one part to yield relative to the other upon encountering resistance before it is interlocked.
- 15 11. In combination with reciprocating duplex means to act upon work, normally inoperative means comprising a sliding member which is interposed between the parts of the duplex means to connect the parts of the duplex means and capable of being maintained inoperative by engagement of an obstruction with said duplex means during the working stroke of said duplex means, and means for rendering said duplex means operative when the path of the element is free.
- 15 12. The combination with a duplex reciprocating working member of a machine, means to link the parts of the duplex working member for movement in unison and movement relative to each other, a sliding member interposed between the parts of the duplex working member, automatic means to operate the sliding member to force it to rigidly connect the parts of the duplex member at a pre-determined point in its working movement for pressure, and automatic means to force the sliding member to a position that will permit the duplex working member to yield if subjected to pressure before it reaches said pre-determined point.
- 15 13. In combination with a duplex reciprocating element and its actuating means, an opposing element, a safety device connected to said element comprising a sliding member which is interposed between the parts of the duplex reciprocating element, means to automatically operate the sliding member to rigidly connect the parts of the duplex reciprocating element to exert a pressure upon work interposed between said elements, and means to render said reciprocating element inoperative if subjected to pressure before it acts upon the work.
- 15 14. In a machine of the class described, the combination of two opposing elements cooperative to exert a pressure upon interposed work, one of which elements is movable toward and from the other, one of said elements being made in two parts, which are connected to move in unison and independent of each other, a sliding member interposed between the parts of the multi-part element, means to force the sliding member to connect the parts of the multi-part element to travel in unison for exerting a pressure and to permit the parts of the multi-part element to yield if subjected to pressure before it reaches a pre-determined point in its travel.
- 15 15. In combination with a duplex work engaging element having an abutment on one of the parts thereof, means interposed between the parts and in one position contacting with the abutment and in a second position being movable without engaging the abutment, and means to actuate the first means to cause said means to engage the abutment when the path of the element to the work is free of any obstruction extraneous to the work.
- 15 16. In combination with a duplex work engaging element the parts of which are normally uncoupled, means to couple said parts, and means to move the coupling means to coupling position when the path of the element to the work is free of any obstructions extraneous to the work.
- 15 17. In combination with a divided reciprocating work engaging element the divisions of which are normally disconnected, and means for positively connecting the division so as to cause same to move in unison when the path of the element to the work is free of any obstructions extraneous to the work.
- 15 In testimony whereof I affix my signature in presence of two witnesses.
